US00D937660S

(12) United States Design Patent (10) Patent No.: US D937,660 S
Marsden (45) Date of Patent: * Dec. 7, 2021

- (54) FURNITURE SECURING DEVICE
(71) Applicant: Elbee Pty Ltd., Bondi Junction (AU)
(72) Inventor: Andrew Marsden, Hingham, MA (US)
(73) Assignee: Elbee Pty Ltd., Bondi Junction (AU)
() Term: 15 Years
(21) Appl. No.: 29/683,693
(22) Filed: Mar. 14, 2019

- Related U.S. Application Data
(63) Continuation of application No. PCT/IB2018/001142, filed on Sep. 12, 2018.
